UNITED STATES PATENT OFFICE.

ALBERT BÜCHI, OF KLOSTERS, SWITZERLAND.

HAND PRINTING APPARATUS.

Application filed January 8, 1927, Serial No. 159,981, and in Germany October 26, 1926.

This invention relates to a hand printing apparatus, which is illustrated on the accompanying drawing, in which

Figs. 1, 2, 3 and 4 are respectively a right-hand side view, a plan view, a left-hand fragmentary side view, and a front view, of the same, and Fig. 5 shows a modification of a detail thereof, Figs. 6 and 7 are respectively a right-hand side view and a fragmentary front view of a modification of the same.

The improved hand printing apparatus is particularly adapted for private use, for providing letters, envelopes or the like with a heading such as an address or the like properly placed thereon.

The improved apparatus comprises a case consisting of a bottom 1, side walls 2 and 3, a rear wall 4 and a cover 5 and having a drawer 6 for the reception of a collection of rubber types therein, while the edges of the bottom 1 and of the cover 5 project laterally beyond the side wall 3 and carry there each a guiding-ledge 7, between which ledges and the outer face of the side wall 3 and respectively between the projecting edges of the bottom 1 and cover 5 a reciprocating slide 8 is guided, said slide carrying two vertical guiding ribs 11, between which an upwardly extending arm 9 is adjustably fixed by means of its slotted open end 10 and a screw-bolt 12 with milled-edged nut 13, said screw-bolt extending from said slide and passing through said slot. Said arm 9 carries by means of a screw-bolt 16 above said box a loosely revoluble, exchangeable printing-roller 14 fitted with the required rubber types 15 which are detachable therefrom, said roller being either plain (14, Fig. 4) or flanged (17, Fig. 5). Said screw-bolt 16 has an integral collar 18 and on both its ends milled-edged nuts 13. With the printing-roller a toothed wheel 19 is detachably connected, the same being in intimate contact with a strip 20 of soft material, such as felt, rubber or the like, fixed on the cover 5 and in which the pointed teeth of said toothed-wheel can be firmly impressed, said strip serving thus as a toothed-rack. Said printing-roller is with its printing surface (rubber types in contact with the cover of said box. The upper end of the arm 9 is

laterally bent and provided with an open slot 21, through which a screw-bolt 22 is passed, the latter being provided—like the bolt 16—with an integral collar 25 and on both its ends with milled-edged nuts 13, by one of which the bolt can be fixed in position within said slot 21 at any height with reference to the printing-roller. The bolt 22 has further an integral collar 24, between which and the other milled-edged nut an inking-roller 23 is fixed directly above the printing-roller.

The operation is as follows:—By a to-and-fro movement of the slide 8 with the arm 9, the printing-roller 14, or 17, is set in reciprocating motion and by means of the toothed-wheel 19 is rotated, whereby the desired printing can be produced on a paper sheet 26 or the like by means of the rubber types 15 on said roller, the latter coming from time to time in contact with the superposed inking-roller 23, the height or depth of which can be adjusted by the bolt 22 as above described.

The inking-roller 23 can be provided with ink from a board 27 with ink-saturated underside placed above the inking-roller and supported by upright brackets 28 on the box.

The strip 20 can be resiliently mounted for instance on spring-pressed pins guided in the cover of the box, this being obviously clear without further illustration.

What I claim, is:—

1. In a hand-printing apparatus, the combination of a box fitted with a drawer, a strip of soft material attached to the cover of said box, a reciprocating slide guided in one side of the latter, an upwardly extending arm fixed to said slide, a printing-roller revolubly mounted on said arm and with its printing surface in contact with the cover of said box, a toothed-wheel detachably fixed at one end of said printing-roller and in intimate contact with said strip of soft material, and an inking-roller revolubly mounted on said arm directly above said printing-roller.

2. In an apparatus as specified in claim 1, means to adjust said arm in its position of height with reference to said box.

3. An apparatus as specified in claim 1,

in which said printing-roller is detachable.

4. An apparatus as specified in claim 1,
in which said inking-roller is adjustable in
its position of height with reference to said
printing-roller.

5. An apparatus as specified in claim 1,
in which said inking-roller is detachable.

6. In an apparatus as specified in claim 1,
an inking-board suspended from said box
and placed directly above said inking-roller. 10
In testimony whereof I have hereunto
set my hand.

ALBERT BÜCHI.
